COLOR FOUNTAIN FOR PRINTING PRESSES

Thomas G. Riordan, San Antonio, Tex.

Application October 14, 1937, Serial No. 169,020

5 Claims. (Cl. 101—350)

This invention relates to a fountain for printing presses, the general object of the invention being to provide a unit including a container for the ink, an ink spreader roller and a rubber roller 5 receiving the ink from the spreader roller, with valve means for controlling the flow of ink from the container to the spreader roller, the unit being so formed that it can be readily put in place on a press with the rubber roller substituted for one 10 of the rollers of the press.

Another object of the invention is to provide a rotary member for intermittently feeding the ink from the container to the spreader roller.

This invention also consists in certain other 15 features of construction and in the combination and arrangement of several parts, to be herein-after fully described, illustrated in the accompanying drawings and specifically pointed out in the appended claims.

20 In describing the invention in detail, reference will be had to the accompanying drawings wherein like characters denote like or corresponding parts throughout the several views, and in which:—

25 Figure 1 is a view looking toward one end of the invention.

Figure 2 is a view looking toward the other end thereof.

Figure 3 is a transverse sectional view through 30 the invention.

Figure 4 is a top plan view thereof.

Figure 5 is a view of the feed roll.

Figure 6 is a section on the line 6—6 of Figure 3.

Figure 7 is a fragmentary sectional view taken 35 approximately on the line 7—7 of Figure 3 to show the tension means for the valves.

In these drawings the numeral 1 indicates a pair of end members between which extends the ink container or hopper 2 which is formed with a flat forward portion on its bottom with the rest of the bottom sloping upwardly and rearwardly so as to direct the ink to the flat portion. This flat portion is provided with a longitudinally extending row of spaced openings 3 each of which 40 is preferably of circular shape and an elongated block 4 extends between the end pieces and has a circular bore 5 extending longitudinally therethrough and the upper portion of the block is formed with the substantially funnel-shaped 45 openings 6 therein which register with the openings 3 in the bottom of the hopper. The small ends of these openings 6 extend through the top wall of the bore 5. A small roller 7 is rotatably arranged in the bore and has a flat portion 7' 50 thereon, see Figure 5, which forms a space for

receiving ink from the hopper when the flat part is uppermost and then as the roller revolves it carries this ink to the bottom of the bore 5 which opens out through the bottom of the block 4 and deposits the ink upon the spreader roller 8 extending between the end pieces and suitably journaled therein, such as by having its trunnions passing through the slots 9 in the end pieces and journaled in the plates 10 fastened to the outer faces of said end pieces. The trunnions of the small 10 roller 7 pass through holes in the end pieces and the upper edges of the plates 10 pass along the lower parts of these holes.

A rubber covered roller 11 extends between the end pieces and contacts the roller 8 to receive 15 the ink therefrom and the ends of the metal core 12 of this roller 11 rotatably engage the cylindrical portions 13 of the flanged members 14 which pass through holes in the front lower portions of the end pieces 1 and have their flanges bolted to the 20 outer faces of the end pieces as shown at 15. By making these bearing members 13 and 14 of cylindrical form and the core 12 in the form of a cylinder a rod can be passed through these parts and the ends of this rod are fitted in the sockets of 25 the printing press after the ink roller of the press has been removed as the roller 11 takes the place of this regular roller of the press.

A shaft 16 is journaled in the rear part of the end pieces and has a large gear 17 on one end 30 thereof meshing with a small gear 18 on one end of the roller 8 and at the other end of the shaft 16 is a small gear 19 meshing with a large gear 20 on one end of the small roller 7. The rubber covered roller 11 is driven by its contact with a drum 35 of the printing press and this roller 11 then drives the steel spreader roller 8 and this roller 8 drives the ink shaft 7 through the gears 18, 17, shaft 6 and gears 19 and 20. Thus it will be seen that the invention needs no driving means as it is driven 40 from one of the rollers or drums of the printing press and this makes it very easy to move the device from one part of the press to another.

A valve rod 22 is provided for each opening 6 and these rods extend through the rear part of 45 the block 4 into the small parts of the openings 6 and they have threaded portions passing through threaded holes in a bar 23 having its ends connected with rear portions of the end pieces 1. A winged head 24 is fastened to the rear end of 50 the rod 22 for turning it for moving the rod longitudinally so that its front end will control the passage of ink through the small part of the opening 6 and this enables the amount of ink 55 passing through the opening to be regulated. A

spring strip 25 passes in a zig-zag manner across the valve rods 22, as shown in Figure 7, the strip passing under alternate rods and over the other rods as shown in this figure so as to hold the 5 rods under tension and thus prevent them from turning accidentally.

A scraper plate 26 is connected to the rear part of the block 4 and has a beveled lower edge engaging the roller 8, as shown in Figure 3.

10 Thus it will be seen that I have provided a one-page portable color fountain which can be easily and quickly placed on a printing press by removing one of the rollers of the press and substituting the fountain therefor, the rubber covered roller 11 taking the place of the removed roller. As will be seen the ink from the hopper 2 will pass through the openings 3 into the openings 6 and pass the inner ends of the valve rods 22, which, of course, should be adjusted to permit 15 the correct amount of ink to pass by them. Then this ink is taken by the roll 7 at intervals and delivered onto the metal roll 8 which delivers the ink to the rubber covered roller 11.

It is thought from the foregoing description 25 that the advantages and novel features of the invention will be readily apparent.

It is to be understood that changes may be made in the construction and in the combination and arrangement of the several parts, provided 30 that such changes fall within the scope of the appended claims.

Having described the invention, what is claimed as new is:—

1. A printing press fountain comprising a 35 frame, a hopper carried by the frame and having a plurality of openings in its bottom, a distributor roller carried by the frame, means for conveying ink from the openings upon the distributor roller and a rubber covered roller carried by the frame 40 and receiving the ink from the distributor roller, said rubber covered roller and its bearing being of hollow construction and adapted to receive a supporting member which is connected with parts of a printing press.

45 2. A fountain for a printing press comprising a supporting frame, bearing members of hollow construction carried by the ends of the frame, a rubber covered roller of cylindrical construction supported by said bearing members, said members and the roller adapted to have a rod pass through the same with its ends fitted in the sockets of one of the rollers of a printing press after such roller has been removed from the press, a metal roller journaled in the frame and 55 contacting the rubber covered roller, a member

supported in the frame above the metal roller and having a bore passing therethrough, the lower part of which opens out through the bottom of the member which is contacted by the top of the metal roller, a small roller rotatably arranged in the bore and having a flattened part, means for rotating the small roller and the metal roller from the rubber covered roller, a hopper supported by the frame, openings leading from the hopper to the bore, valve rods extending into 10 said openings, manually operated means for adjusting the rods and means for holding the rods under tension.

3. A printing press fountain comprising a frame, a hopper carried by the frame and having a plurality of openings in its bottom, a distributor roller carried by the frame, means for conveying ink from the openings upon the distributor roller, a rubber covered roller carried by the frame and receiving the ink from the distributor 20 roller, said rubber covered roller being driven from a part of the printing press and said rubber covered roller rotating the distributor roller and means for actuating the ink conveying means from the distributor roller.

4. A fountain for a printing press comprising a supporting frame, a hopper carried by the frame and having a plurality of openings in its bottom, a member carried by the frame and having openings therein registering with the first-mentioned 30 openings, and said member having a bore, a roller passing through the bore and having a flattened part for forming a space for receiving ink from the hopper when said flattened part comes under the openings, a distributor roller receiving 35 the ink from the first-mentioned roller, means for rotating the roller having the flattened part from the distributor roller, a rubber covered roller contacting the distributor roller and valve means for regulating the amount of ink passing 40 through the openings leading to the bore.

5. A fountain for a printing press comprising a supporting frame, a hopper carried by the frame and having an opening in its bottom, a member carried by the frame and having an opening therein registering with the first-mentioned opening and said member having a bore, a roller passing through the bore and having a flattened part for forming a space for receiving ink from the hopper when said flat part comes 45 under the opening, a distributor roller receiving the ink from the first-mentioned roller and a third roller contacting the distributor roller for receiving ink therefrom.

THOMAS G. RIORDAN. 55
